UNITED STATES PATENT OFFICE.

CLEMONS H. DAVIS, OF CINCINNATI, OHIO.

DESIGN FOR A VEHICLE-SEAT.

SPECIFICATION forming part of Design No. 36,985, dated June 14, 1904.

Application filed May 29, 1903. Serial No. 159,392. Term of patent 3½ years.

To all whom it may concern:

Be it known that I, CLEMONS H. DAVIS, a citizen of the United States, residing at Cincinnati, in the county of Hamilton and State 5 of Ohio, have invented a new, original, and ornamental Design for Vehicle-Seats, of which the following is a specification, reference being had to the accompanying drawing, forming part thereof.

• The accompanying drawing illustrates a perspective elevation of a new, original, and ornamental design embodying my invention.

I claim—

The ornamental design for a vehicle-seat as shown.

CLEMONS H. DAVIS.
